(57) **CLAIM**

The ornamental design for a base for luminary, as shown and described.

DESCRIPTION

FIG. 1 is a perspective view showing a first embodiment of our new design.

FIG. 2 is a left side view of the design of FIG. 1.

FIG. 3 is a right side view of the design of FIG. 1.

FIG. 4 is a front view of the design of FIG. 1.

FIG. 5 is a rear view of the design of FIG. 1.

FIG. 6 is a top view of the design of FIG. 1.

FIG. 7 is a bottom view of the design of FIG. 1.

FIG. 8 is a perspective view of a second embodiment of our new design.

FIG. 9 is a left side view of the design of FIG. 8.

FIG. 10 is a right side view of the design of FIG. 8.

FIG. 11 is a front view of the design of FIG. 8.

FIG. 12 is a rear view of the design of FIG. 8.

FIG. 13 is a top view of the design of FIG. 8; and,

FIG. 14 is a bottom view of the design of FIG. 8.

The broken-line disclosure in the views is understood to represent portions of the article in which the claimed design is embodied, but which do not comprise part of the claimed design. Where a broken-line abuts a claimed surface, that broken line is understood to indicate either an unclaimed edge or an unclaimed boundary between claimed and unclaimed surfaces.
